UNITED STATES PATENT OFFICE.

CHARLES W. STRUBLE, OF WAUSEON, ASSIGNOR TO JACOB M. LONGNECKER, OF DELTA, ALBERT L. FLACK, OF TIFFIN, AND HENRY S. HULL, OF WAUSEON, OHIO.

FOLDED BOX OR PAIL.

SPECIFICATION forming part of Letters Patent No. 390,266, dated October 2, 1883.

Application filed February 28, 1883. Serial No. 265,620. (No model.)

To all whom it may concern:

Be it known that I, CHARLES W. STRUBLE, a citizen of the United States, residing at Wauseon, in the county of Fulton and State of Ohio, have invented new and useful Improvements in Folded Boxes or Pails, of which the following is a specification.

My invention relates to improvements in folded boxes or pails, and has for its object to form a pail wherein the body is provided with a cover secured permanently by means of the bail or handle and of such construction that it will not readily become crushed or broken.

In the drawings, Figure 1 is a perspective view of a pail having my improved cover attachment. Fig. 2 is a longitudinal section on the dotted line $x-x$, Fig. 1. Fig. 3 is a transverse section showing the cover in position. Fig. 4 is a horizontal section on line $y-y$, Fig. 2,

Referring by letter to the drawings, A designates the body of the pail, which may be of any suitable construction and material, and has the ends of the wire bail B passed through its front and rear and bent parallel with the interior face of the pail.

The pail A is of the ordinary construction, many examples of which may be seen in the markets at this day. The construction thereof and its method of manufacture from a single piece of paper being obviously apparent and not constituting my invention, it is not necessary to further enlarge upon the same herein. The folding of the box leaves spaces between the ends and the folded diagonal flaps, and these spaces provide pockets C C, to receive the free ends of the cover, (see Fig. 4,) and also ledges d, Fig. 2, at the top edges of the ends, on which ledges the free edge of the cover rests.

The cover D comprises the main fold E, the rear or hinged flap, F, the leaves G G on the front edge of the main fold, and the side strips, H. A small handle, I, is secured on the main fold, near its front edge, to enable the cover to be readily raised.

The rear or hinged flap, F, is placed parallel with the inner face of the rear end of the body, and is secured in position by the bent end b' of the bail passing through the same. The crease or bend between the main fold E and

the hinged fold F is arranged, as will be seen, at the upper edge of the rear fold, and as the hinge-fold is secured rigidly to the body this crease will serve as a hinge to allow the cover to be raised at will. The leaves G G are adapted, when the cover is in its closed position, to enter the pockets C, so as to properly support the cover in connection with its fastening. The side strips, H, pass inside of the upper edges of the sides of the body.

A lining of paper may be secured within the box. This lining is shown in the drawings and lettered f'. In practice this lining is cut from a blank similar to the blank which forms the pail proper, so that when the pail is folded the lining will fit neatly and accurately the inside of the pail. The lining may or may not be secured to the body of the pail by some adhesive substance.

The leaves G G are separated by means of a V-shaped notch, which provides for the bent end b of the bail and allows said flaps G G to pass well down into the pockets. The side strips also prevent the sides of the pail from bulging outward, as will be seen.

It will be obvious that by utilizing the end of the bail to secure the cover a simple and efficient arrangement is provided and the cover will not become accidentally detached from the pail and lost.

To obtain access to the interior of the box, the bail is swung down to one side, when the cover can then be raised a sufficient distance.

Having described my invention, I claim—

1. The combination of the pail-body, the cover on the top thereof and provided with a rear hinged flap and front leaf, as described, and a bail secured to the body and engaging the hinged flap to fasten it in position, substantially as described.

2. The combination of the body having the pocket on the inner face of its front, the cover provided with a rear hinged flap and front leaves, G G, separated by V-shaped notch, and a bail secured to said body and attaching the cover in position, substantially as described.

3. The pail comprising the body, the cover on the top thereof, having the rear hinged flap and side strips, and the bail secured to the

body and engaging the hinged flap to fasten it to the body, as set forth.

4. The combination of the body having the pockets C C, the cover provided with the rear hinged flap and front leaves, G G, adapted to take into the respective pockets, and a bail secured to the body and engaging the cover to permanently retain it in place, as set forth.

10 5. In a pail, the body, the cover on the top thereof provided with a hinged flap, as de-

scribed, and a bail secured to the body and engaging the hinged flap to fasten it in position, as set forth.

In testimony that I claim the foregoing as my 15 own I have hereto affixed my signature in presence of two witnesses.

CHARLES W. STRUBLE.
